ASH TRAY

Gus Scharles and Harry J. Storms,
New York, N. Y.

Application January 20, 1940, Serial No. 314,786

9 Claims. (Cl. 131—242)

This invention relates to ash trays, more particularly of the type intended for use by cigarette smokers.

One of the objects of this invention is to provide a practical device of the above-mentioned character for dependably receiving ashes, cigarette butts, and the like, and for safely and reliably supporting a lighted cigarette. Another object is to provide a cigarette ash tray and support in which danger of a lighted cigarette or lighted cigarette butt falling onto the table, table cloth, or like part supporting the device, is dependably guarded against. Another object is to provide a device of the above-mentioned character which will be inexpensive to manufacture, durable in construction, and of reliable action in use. Another object is to provide an ash receiver and cigarette holder which will readily lend itself to wide adaptability to meet various conditions of practical use.

Another object of this invention is to provide a device of the above-mentioned character capable of embodiment in such a way that, particularly when the device is not in use, it may be folded or assembled into neat compact form, though readily rearranged for practical use when desired. Another object is to provide a device of the just stated character in which its individual parts may be of simple and inexpensive construction and capable of ready and convenient assembly or manual rearrangement as desired. Another object is to provide an ash tray or receptacle with a movable part or parts whereby the device may be arranged in completely enclosed relation, thus to avoid unsightliness of its contents, or may be arranged in opened relation for the reception of ashes and the like and for properly positioning the retaining means for lighted cigarettes.

Another object is to provide a construction of the above-mentioned character capable of being made inexpensively out of various materials.

Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing in which are shown illustratively several of the various possible embodiments of our invention:

Figure 1 is a perspective view of one form of device, shown in closed relationship;

Figure 2 is a perspective view with certain parts broken away of the device in open or operating relationship;

Figures 3, 4 and 5 are respectively sectional views as seen along the line 3—3, 4—4 and 5—5 of Figure 2;

Figure 6 is a perspective view of another form of device shown in closed relationship, certain parts being broken away, and

Figure 7 is a perspective view, with certain parts broken away, of the device of Figure 6 shown in opened and operating relation.

Similar reference characters refer to similar parts throughout the several views in the drawing.

Referring first to Figures 1 and 2 of the drawing, we prefer to embody the device to provide two portions, one portion indicated generally by the reference character 10, providing or forming a receptacle for ashes, or the like, and another portion generally indicated by the reference character 11, providing a means for controlling a lighted cigarette, as is later described in greater detail; preferably the portions 10 and 11 comprise separate or individual parts, respectively, and in such case are related to each other for relative movement therebetween.

The portion 10 may be given any suitable shape or conformation and as better appears in Figure 2 it may, for example, be shaped to be in cross-section generally rectangular. It therefore preferably has a bottom wall 12, opposed side walls 13, 14, and end wall 15, and opposed to the latter is an end wall 16 which preferably is part of the portion 11 later described. These parts may be dimensioned to give an interior ash-receiving space of the desired volume.

The portion 11, preferably constructed to embody in it end wall 16, as above noted, preferably also has embodied in it what, when the parts are in the position shown in Figure 1, is a top or closure wall 17, and in the illustrative embodiment the wall parts 16 and 17 form a right angle to each other and within that angle, and preferably integrally formed with the wall parts 16 and 17 and within the angle encompassed thereby we provide a structure, illustratively somewhat in the form of a pedestal 18 of a thickness on the order of that of a cigarette; in height, at its left-hand end, as seen in Figure 2, the pedestal part 18 is about the same height as the end wall 16, and in length at its base it extends from the end wall 16 almost to the right-hand end of the top wall 17. It is otherwise shaped to provide a substantially horizontal

trough 19 which, as is better shown in Figure 2, also cuts through the end wall 16 at its left-hand end, while at its right-hand end the trough 19 has a downwardly and outwardly sloping extension trough 20 whose right-hand or lower end terminates preferably at or adjacent the plane of one face of the wall part 17.

Where the device is made up of two separate parts, like the portions 10 and 11, we preferably construct the two portions to permit ready change in their relative relationships, say from the closed relationship of Figure 1 to the opened or operating relationship of Figure 2, or vice versa; in the form of Figures 1 and 2 this may be achieved as by pivotally connecting the two portions, say by a pivot pin or pins 21, the axis of which passes through the end wall part 16, preferably midway of its vertical dimension, and the two side walls 13 and 14. Thus, the portion 11 may be swung about the axis of the pivotal connection 21 to bring the end wall 16 and top wall 17 into the closing position shown in Figure 1 or to bring the portion 11 into the position shown in Figure 2 where the end wall 16 remains in position to coat with the walls 12, 13, 14, 15 to form an ash receiver while the wall 17 extends laterally from the latter to expose the pedestal 18 with the angularly related troughs 19 and 20 upwardly for use in confining, for example, a lighted cigarette. In this relationship the portion 11 projects or extends laterally from the ash receiver portion 10 and it may or may not contact with or rest upon the surface, such as a table top, which supports the receiver portion 10. The parts are preferably so proportioned or hinged connected together that the outer or right-hand under edge of the part 17, as viewed in Figure 2, contacts the table top or other supporting surface.

When so disposed, a lighted cigarette may be safely set down, as by laying it into the upper trough portion 19 with the lighted end overhanging the interior of the receiver portion 10, and though neglected or forgotten the device thereafter controls the cigarette so that it will not find its way to the table top or other supporting surface. Both trough portions 19 and 20 are preferably concaved, as appears better from Figures 3 and 4, giving them a radius of curvature substantially the same as that of the cigarette which, in Figures 3 and 4, is indicated by the reference character C. As the lighted end of the cigarette burns away, and if it is of such initial length that a substantial portion overhangs the right-hand end of the trough 19, the creation of a condition of unstable equilibrium effects a tilting of the cigarette in clockwise direction, as viewed in Figure 2, about the right-hand end of the trough 19 as a fulcrum, thus swinging the mouth end of the cigarette into the downwardly sloping trough 20 whose upper side edges, as better appears from Figure 4, dependably restrain or control the cigarette against falling or rolling out of the trough. When such tilting of the cigarette C takes place and depending upon its length, the cigarette may also slide down the inclined trough 20 at whose lower end we preferably provide a suitable stop preferably in the form of an abutment shaped to provide a circular face or surface 22 (Figures 2 and 5) of a diameter on the order of the diameter of the cigarette. The face 22 is preferably at right angles to the axis of the sloping trough 20 and the downwardly sliding cigarette is brought to rest by its own end face, generally circular, engaging the face 22

which, being, in the preferred form, at right angles to the axis of the cigarette, also acts to resist any tendency of any momentum or reaction of the moving cigarette to cause it to partake of a subsequent tilt about its own end face as an axis. Preferably, the face 22 of the abutment has extending about so much of it as does not coincide with the cross-section of the trough 20 a ridge 23 which at its two ends merges into the ridge-like edges that form the outer longitudinal portions of the trough 20 and the inner face of the ridge 23 is preferably sloped or frustoconical to give it a funnel-like effect, thus to aid in guiding a downwardly sliding cigarette into engagement with the face 22 and to aid also in resisting any subsequent tilting tendency as above-mentioned.

Thus, a burned cigarette is dependably controlled even though it remains unattended or neglected and it cannot find its way to the table top or, for example, to the table cloth, even though such physical changes take place in the cigarette as cause it to change its initial position in the trough 19. Preferably, the trough 19 and also the trough 20 are concaved, as earlier above-mentioned, for, with a substantially snug interfitting of the cigarette with the walls of the concave trough, the fire of the cigarette usually extinguishes itself by the time it reaches that portion of the cigarette that is initially placed in the trough 19. A subsequent tilting of the cigarette into the trough 20 may thus find the cigarette extinguished. If it is not extinguished upon tilting into the trough 20 the relative snug engagement between the cigarette and the concave walls of the trough 20 then effects extinguishing of the fire. But whether or not the fire is extinguished, the movement or movements of the cigarette are dependably controlled and the cigarette does not escape to the table or other support.

Preferably, the upper face of the wall part 17, as viewed in Figure 2, is curved or otherwise made to slope toward its edges so as to make it impossible intentionally or otherwise to rest a cigarette thereon; thus, a lighted cigarette must be positioned in the receiver portion 10 or appropriately related to the trough of the portion 11. The receiver portion 10 may be given any desired depth internally and preferably, particularly where it is of substantial depth, we prefer to provide it also with an internal ledge 24 (see Figure 2) preferably of substantial area so as to present an upper face large enough to permit tamping or crushing the fire of a cigarette thereagainst; this ledge 24 we preferably position at the left-hand end of the receiver portion 10 and preferably at such a height that it serves as a stop or rest for the free end of the wall portion 17 when the latter is swung into closing position, as shown in Figure 1, and where necessary the ledge 24 may have a cutout as at 25 (Figure 2) to let the abutment bearing the parts 22, 23 (Figures 2 and 5) by-pass the ledge. The ledge 24 thus limits the extent to which the portion 11 may swing in counter-clockwise direction and thus we may make certain that the outer faces of the top wall 17 and of the end wall 16 are, in this closing relationship, as shown in Figure 1, nicely aligned with the edges of the walls of the receiver portion 10. Thus, when in enclosed relationship, the device may be made to present a neat and compact appearance.

From the relationship of Figure 1 the device is quickly and easily rearranged for use, as

shown in Figure 2, by simply swinging the portion 11 in clockwise direction about the axis of the pivot pin or pins 21; in this connection a manual pressure exerted inwardly of the end wall 16 below the axis of the pivot pin 21 suffices to start the swinging movement. With the portion 11 swung into a position intermediate of the two extremes shown in Figures 1 and 2, say, for example, when swung 90° from either of these extremes, emptying of the receiver portion 10 is facilitated since its contents may simply be slid off of the bottom 12 of the receiver portion 10 and out through the right-hand end of the portion 10 which, with the end wall 16 thus in substantially horizontal position, is thus open for the discharge of ashes, butts, etc.

The construction lends itself to manufacture out of a wide variety of materials. Thus, its various parts may be readily cast, as out of metal, it may be made up of moldable plastics, it may be built up out of sheet metal, etc., ceramics and glass and like materials may also be employed; under some circumstances it might be inexpedient or undesirable, possibly because of the type or kind of material employed, to provide for a pivotal connection between the two portions 10 and 11. In such or other cases as may be desired, the two portions may be related to each other for relative movement in ways other than the pivotal connection of Figures 1 and 2, and an arrangement like that shown in Figures 6 and 7 might be employed.

In the structure of Figures 6 and 7, we prefer to arrange the portions 10 and 11 for detachable interconnection with each other so that the two relationships typified in Figures 1 and 2 may be achieved at will. Thus, instead of the pivotal connection provided by the pivot pin or pins 21 of Figures 1 and 2 between the opposed ends of the side walls 13, 14 and the movable end wall 16, in the structure of Figures 6 and 7, the inner faces of the ends of the side walls 13, 14 are provided with parallel vertically extending grooves 26, 27, respectively, and preferably extending throughout the vertical dimension of these side walls, and in the vertical end edges of the end wall 16 we provide tongues 28, 29 also preferably extending throughout the vertical dimension of the end wall 16 and enterable, respectively, into the grooves 26, 27.

Thus, the portion 11 may be assembled to the portion 10 to give the closed or enclosed relationship shown in Figure 6 by a relative vertical movement between the two portions in such a way as to enter the above-mentioned tongues into their respective grooves, thus bringing the end wall into closing relation at the end of the device and thus bringing the wall portion 17 into closing relation at the top of the device, all as is clearly shown in Figure 6. Preferably, also, the left-hand end of the under face of the top wall portion 17 when in the position of Figure 6 comes to rest against the ledge 24, as was described in connection with Figures 1 and 2.

When use is to be made of the device, the portion 11 in Figure 6 is separated from the portion 10 by a relative vertical movement between the two, whence the portion 11 is then turned in clockwise direction through 180°, thus to invert the end wall 16, whence the two portions are reassembled by entering the tongues 28 and 29 into the grooves 26 and 27, respectively, again bringing the wall 16 in receiver-closing position, but with the wall portion 17 now extended laterally from the receiver portion 10 and exposing

upwardly the cigarette retainer or control troughs and parts, all as shown in Figure 7, whence the use and functioning of the device may proceed in the manner above described in connection with Figure 2.

With the arrangement of Figures 6 and 7, we may somewhat enlarge the wall portion 17, as appears better from Figure 6, so that it may overlie the upper end edges of the walls 13, 15 and 14 which may thus take part in supporting the part 17 and coact with the ledge 24 in limiting the extent of downward movement of the portion 11 when assembled to the portion 10, as in Figure 6. These parts may be so proportioned also as to come to rest with respect to one another at the same time that the bottom edge of the end wall 16 (Figure 6) comes to rest on the bottom wall 12 of the receiver portion 10.

By changing the dimensions and proportions of the top wall 17, as above suggested, we may also and thereby provide a rabbet-like effect, as at 30 (Figure 6) between the right-hand end edge of the wall portion 17 and the upper end edge of the end wall 16, the vertical dimension of the rabbet, as seen in Figure 6, being preferably the same as the thickness of the bottom wall 12. Accordingly, when the portion 11 is pivoted from the relationship of Figure 6 to the relationship of Figure 7, the rabbet-face or edge 16a of end wall 16 comes into engagement with the upper face of the bottom 12 and the rabbet-face or edge 17a of the wall portion 17 virtually mates with the end edge 12a of the bottom wall 12. By way of a construction such as this, therefore, we are enabled to bring the under face of the bottom 12 and the under face of the wall 17, when the parts are in the relationship shown in Figure 7, into the same plane, and thus the two assembled portions 10, 11, though connected, may rest flatwise upon the same surface, such as a table, or the like. Thereby, the possibility of subjecting the tongue and groove connections between the two portions to undesired strains or stresses is minimized.

The use of the form of Figures 6 and 7 will now be clear in view of what has been set forth above, particularly also in connection with Figures 1 and 2. Cleaning or emptying of the receiver portion 10 may also be easily effected for the right-hand end of the receiver portion 10 may be conveniently and quickly opened simply by sliding the portion 11 upwardly, thus to move the end wall 16 out of closing position (analogous to the substantially horizontal or intermediate position of the wall 16 in Figure 2) and permitting the contents of the receiver portion 10 to be dumped or slid out of the thus open ended device.

Thus, it will be seen that there has been provided in this invention an ash tray and cigarette-restricting or retaining device in which the various objects hereinbefore stated, together with many thoroughly practical advantages are successfully achieved. It will be seen that the device is of simple but durable construction, lends itself to manufacture out of a wide variety of materials and in such variety of materials without high cost of manufacture. Moreover, it will be seen that it is of a thoroughly practical character and in practical use dependably provides against the otherwise grave risks accompanying the laying down of lighted cigarettes. Moreover, the device can readily serve to extinguish or smother lighted cigarettes or cigarette butts as, for example, by restoring the

relationship shown in Figures 1 and 6, thus substantially totally enclosing any lighted cigarettes or cigarette butts that are placed within the receiver portion 10. Thus, it will be seen that the device is of a thoroughly practical nature.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

We claim:

1. A smoker's appliance comprising two portions, one of which has a bottom wall, two opposed side walls and only one end wall, the other portion having a part that provides an end wall for said first portion opposed to said first-mentioned end wall and another part extending at an angle thereto and being in extent commensurate with the extent of said bottom wall, with cigarette-retaining means accommodated in the angle between said two parts of said second portion, and means connecting said two portions to permit them to be related to each other selectively in any of several relationships, in two of which relationships said end wall part of said second portion is in position opposed to said end wall of said first portion and in one of which two relationships said second-mentioned part of said second portion is opposed to the bottom wall of said first portion and closes the latter with said cigarette-retaining means projected into said first portion and in the other of which two relationships said second-mentioned part of said second portion extends away from said first portion to expose said cigarette-retaining means externally of said first portion and leaves said first portion open at the top, but closed around its sides and ends for the reception of ashes or the like, said connecting means providing for another of said several relationships in which said second portion is positioned relative to said first portion to bring said end wall of said second portion out of position to completely close off the ends and sides and whereby, as by tilting said first portion downwardly about its only end wall as an axis and thereby sliding said ashes out from in between its side walls, discharge of ashes or the like from said first portion may be effected.

2. A construction as claimed in claim 1 in which said connecting means is in the form of a pivotal connection between said two portions with the axis of pivoting so positioned as to permit a swing of one portion relative to the other of substantially 180° to effect transition from one of said two relationships to the other and to establish said last-mentioned relationship for discharge of ashes when one portion is swung relative to the other to an angle of swing intermediate the extremes of said 180°.

3. A construction as claimed in claim 1 in which the connecting means between said two portions comprises means on both of the latter for selectively interfitting said two portions to provide selectively any of said relationship.

4. A construction as claimed in claim 1 in which the connecting means between said two portions comprises means on said two portions connecting them for relative and reversible movement therebetween for thereby selectively positioning said second portion with its end wall portion and other wall portion in complete closing relation to said first portion or with said

end wall part of said second portion opposed to the end wall of said first portion and with the remaining parts of said second portion extending outwardly and away from said first portion 5 and thereby exposing said cigarette-retaining means.

5. A construction as claimed in claim 1 in which said first portion and the end wall part of said second portion have tongue and groove 10 means forming the said connecting means between said two portions.

6. A construction as claimed in claim 1 in which said connecting means comprises means pivotally connecting said two portions for pivoting movement relative to each other about an axis substantially midway of the vertical dimension of said end wall part of said second portion whereby said second portion may be swung relative to the first portion to invert the end wall part 20 of said second portion and to position said cigarette-retaining means either interiorly or exteriorly of said first portion, thereby establishing either of said two relationships, said pivotal connecting means permitting positioning of said second portion relative to the first portion at an intermediate position to establish said other relationship for discharge of ashes.

7. A smoker's appliance comprising means forming a container for ashes or the like and 30 having a bottom and retaining side wall means of which side wall means a part is movable relative to the rest, said movable side wall part having an extension that extends at an angle thereto and that is in extent sufficient to close said container means when positioned opposite said bottom, there being cigarette-retaining means in the angle between said side wall part and said closure-forming extension and mechanically connected to both, and means forming a connection 35 between said relatively movable parts of the appliance to permit relating said side wall part to the rest of said side wall means selectively in either of two relationships in one of which said retaining means projects laterally away from said container means and in the other it projects inwardly of the latter and said extension is opposite said bottom, there being within said container means a rest for the reception thereagainst of a cigarette butt or the like and spaced upwardly 40 from said bottom and thereby positioned to form an internal support for a part of said extension when the latter is opposed to said bottom.

8. A smoker's appliance comprising means forming a container for ashes or the like and having a bottom and retaining side wall means 45 of which side wall means a part is movable relative to the rest, said movable side wall part having an extension that extends at an angle thereto and that is in extent sufficient to close said container means when positioned opposite said bottom, there being cigarette-retaining means in the angle between said side wall part and said closure-forming extension and mechanically connected to both, and means forming a connection 50 between said relatively movable parts of the appliance to permit relating said side wall part to the rest of said side wall means selectively in either of two relationships in one of which said retaining means projects laterally away from said container means and in the other it projects inwardly of the latter and said extension is opposite said bottom, said cigarette-retaining means comprising two connected trough-like portions of which one extends from said side wall part substantially parallel to said extension and the other 55

slopes downwardly therefrom to the latter and together they coact to resist change in the angularity between said side wall part and its extension.

9. A smoker's appliance comprising means forming a container for ashes or the like and having a bottom about which extends retaining side wall means of which side wall means a part is separate from the rest and is pivotally connected to the latter to swing about an axis intermediate the upper and lower ends of said separate part, said separate part having an extension that extends at an angle thereto and that is in extent sufficient to close said container, there being cigarette retaining means mounted in the 15

angle between said separate side wall part and said closure-forming extension, whereby, when said extension is in container-closing position, said cigarette retaining means is inside of said 5 container, that portion of said separate side wall part that extends below said axis of pivoting forming a finger-piece lever arm which, when pressed inwardly, swings said separate part in a direction to swing said extension out of container-closing position so that said container may receive ashes or the like and brings said cigarette retaining means into exposure for the reception thereon of a cigarette.
